CLAIM

The ornamental design for an surf wax scraper and comb, as shown and described.

DESCRIPTION

The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a first-perspective view of a surf wax scraper and comb including a first portion, second portion and third portion showing our new design;

FIG. 2 is a second perspective view thereof;

FIG. 3 is a top view thereof;

FIG. 4 is a bottom view thereof;

FIG. 5 is a front view thereof;

FIG. 6 is a back view thereof;

FIG. 7 is a side view thereof;

FIG. 8 is a first-perspective view of the first portion of the surf wax scraper and comb;

FIG. 9 is a second perspective view thereof;

FIG. 10 is a top view thereof;

FIG. 11 is a bottom view thereof;

FIG. 12 is a front view thereof;

FIG. 13 is a back view thereof;

FIG. 14 is a side view thereof;

FIG. 15 is a first-perspective view of the second portion of the surf wax scraper and comb;

FIG. 16 is a second perspective view thereof;

FIG. 17 is a top view thereof;

FIG. 18 is a bottom view thereof;

FIG. 19 is a front view thereof;

FIG. 20 is a back view thereof;

FIG. 21 is a side view thereof;

FIG. 22 is a first-perspective view of the third portion of the surf wax scraper and comb;

FIG. 23 is a second perspective view thereof;

FIG. 24 is a top view thereof;

FIG. 25 is a bottom view thereof;

FIG. 26 is a front view thereof;

FIG. 27 is a back view thereof; and,

FIG. 28 is a side view thereof.

This patent document may show and/or describe matter which is or may become trade dress of the owner.
